UNITED STATES PATENT OFFICE.

SYDNEY SMITH, OF GLASGOW, SCOTLAND.

ROTARY ENGINE.

SPECIFICATION forming part of Letters Patent No. 699,720, dated May 13, 1902.

Application filed August 2, 1900. Serial No. 25,707. (No model.)

To all whom it may concern.

Be it known that I, SYDNEY SMITH, a subject of the Queen of Great Britain and Ireland, residing at Glasgow, Scotland, have 5 invented a new and useful Improvement in Rotary Engines, (for which I have made application for Letters Patent in Great Britain under No. 265, dated January 4, 1900,) of which the following is a specification.

10 This invention relates to improvements in rotary engines, and has for its object the balancing of the turning and inertia moments and the radial pressure set up by the motive fluid about the axis, so that the axle does not 15 press or react unduly upon the bearings, but practically floats therein, the provision of means for reducing the friction and wear of the reciprocating abutment and to enable it to follow and make a good sliding joint with 20 the cam-piston, the automatic lubrication of the reciprocating abutment, and the specific arrangement of packing on the parts having relative movement to maintain a tight sliding joint.

25 In order that my invention may be the better understood, I will now proceed to describe it in relation to the accompanying drawings, reference being had to the letters marked thereon.

30 Like letters refer to like parts in the various figures.

Figure 1 is a part-sectional view of my improved engine. Fig. 2 is an end sectional elevation of the same. Figs. 3 and 4 show various details of the parts of my engine. Fig. 35 5 is a longitudinal section of the cam-piston in Fig. 4. Fig. 6 is a transverse section of the same.

It will be seen from the drawings that I 40 range upon each side of a central cylinder A another cylinder B, of such a length and diameter that the effective area of the cam-piston C of the cylinder A equals the sum of the effective areas of the cam-pistons D of the 45 cylinders B. The two cam-pistons D are mounted on the axle E at an angle of one hundred and eighty degrees to the cam-piston C. This arrangement gives a perfect balance 50 of turning and inertia moments and of the radial pressure. Each cylinder is provided with a lateral casing or box F, in which slides a reciprocating abutment G, having a circu-

lar seating g, into which rests a segmental packing-piece H, adapted to rock in the seatings so as to adapt its edge or surface to the 55 periphery of the cam-piston during the passage of the latter in its circular path in the cylinder. Within the packing-piece H are mounted antifriction-rollers I, which rest upon the surface of the cam-piston, and thus reduce the friction and retarding effort of the abutment G on the piston. I also arrange antifriction-rollers J upon the sides of the box or casing F, so as to take the canting strains 60 set up on the abutment by the action of the 65 cam-piston in its travel.

Upon the cover of the box F, I arrange a lubricating pump-barrel K, which, coacting with a pipe-plunger L, carried by the abutment G, forms a small lubricating-pump for 70 delivering a small quantity of oil from a lubricator or other source of oil to the surface of the circular seating g. Suction and delivery valves l l' are provided to produce the proper pumping effect during working. 75

At various parts of the engine I provide a special form of packing for maintaining the rubbing-surfaces tight. This is illustrated in Figs. 1, 2, and 4, and consists in the case of the cam-piston, for example, of an outer metallic 80 rubbing-piece M, held in a diagonally-disposed groove M'. Below the rubbing-piece M is a layer of soft fibrous packing M², such as asbestos, and under this a metallic strip M³, spring-pressed outward by metallic springs 85 M⁴, resting on the bottom of the groove M', so as to force the packing outward and at the same time expand the soft packing M² outward 90 to make a joint against the sides of the groove to prevent the passage of the gaseous fluid 95 thereby. The horns M⁵ on the metallic strip M have inclined faces, so as to gradually depress the strip when passing the abutment. These horns lie freely in their grooves in the cam-piston, so that the pressure of the motive fluid in the cylinder acts freely on all the surfaces of the horns in order to prevent such pressure on the horns depressing the strip in the groove.

The packing N around the abutment G is 100 somewhat similar in construction; but instead of the metallic rubbing-piece the soft packing is held in a frame N', so as to bear against the sides of the groove and also the

face of the abutment. This packing has a metallic strip N^2 at its back, which is set up by screws in the sides of the casing. The abutment G is forced downward in contact with the cam-piston by a spiral spring P and the steam-pressure.

The cylindrical parts joining the cam-pistons C and D are provided with rams bottom or similar rings o , which rubbing against the adjacent surfaces maintain a steam-tight joint between the cylinders. The arrangement of rings o , soft packing r , and holding ends s , provided with tightening-ring t , is such that the pressure on the two sides of the rings o is equalized to a great extent. The rings o may be made with an initial spring or tension or compression and may be gripped laterally when the rubbing-surfaces are in contact, so as to retain them in position.

20 The steam or other motive fluid is admitted to the engine by the pipe U , leading to the valve-box V , having a reciprocating balanced valve v , driven by an eccentric W and rod w . This box V has two ports $X X'$, one communicating by a pipe x with the central cylinder and the other by two pipes $x' x'$ with the side cylinders $B B$. This valve v controls the admission and rate of expansion of the motive fluid. The exhaust from the engine 25 passes off by the orifice Y in each of the cylinders.

Having now described my invention, what I claim, and desire to secure by Letters Patent, is—

30 1. In a rotary engine, a cylinder, a cam-

piston, in combination with a sliding abutment provided with a circular seating, a segmental packing-piece adapted to rest in the seating and make sliding contact with the periphery of the cam-piston, and an antifriction roller or rollers within the segmental packing-piece adapted to roll on the periphery of the said cam-piston, substantially as described.

2. In a rotary engine, a cylinder and a movable abutment in combination with a cam-piston having a diagonal groove containing the peripheral packing consisting of a metallic packing-piece having horns with inclined surfaces, a layer of soft fibrous packing filling up the space in the groove below the metallic piece, a metallic supporting-strip below the fibrous packing and springs arranged at the bottom of the groove to compress the fibrous packing and press the whole packing outward substantially as described.

3. In a rotary engine a cylinder, a cam-piston, and a movable abutment in combination with a lubricating pumping device operated by the reciprocation of the movable abutment to pump lubricant to the rubbing-surfaces of the abutment and to the interior of the engine, substantially as described.

In witness whereof I have hereunto set my hand in presence of two witnesses.

SYDNEY SMITH.
